UNITED STATES PATENT OFFICE.

ADOLPH VLK, OF CHICAGO, ILLINOIS.

DESIGN FOR A COMBINED AUTOMOBILE RADIATOR, HOOD, AND COWL.

Application filed March 5, 1929. Serial No. 30,324. Term of patent 7 years.

To all whom it may concern:

Be it known that I, ADOLPH VLK, a citizen of the United States, residing at 4111 West 22nd Street, in the town of Chicago, county of Cook and State of Illinois, have invented a new, original, and ornamental Design for a Combined Automobile Radiator, Hood, and Cowl, of which the following is a specification, reference being had to the accompanying drawing, forming part thereof:

Figure 1, is a front view of a combined automobile radiator, hood, and cowl, embodying my new and ornamental design, and Figure 2, is a perspective view of same.

I claim:

The ornamental design for a combined automobile radiator, hood, and cowl as shown.

ADOLPH VLK.
